OIL BURNER

Filed Nov. 2, 1928

UNITED STATES PATENT OFFICE

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS

OIL BURNER

Application filed November 2, 1928. Serial No. 316,677.

My invention relates to oil burners of the centrifugal atomizer type and is concerned especially with an improved feed for the fuel oil from a stationary fuel supply member on 5 to the rotary atomizer.

My present invention may be considered as an improvement on that disclosed in my co-pending application Serial No. 748,862, filed November 10, 1924.

10 As compared with the structure disclosed in that application, the object of my present improvement is to eliminate the tendency of oil passing the narrow annular gap between the stationary feed member and the rotary 15 feed member of the atomizer from traveling downwardly along the fuel delivery stand pipe.

Another object of my invention is to provide for the vertically journaled atomizer a 20 cover which will prevent dirt from dropping down into the mouth of the atomizer but will not interfere with cleaning of the interior of the atomizer.

These and further objects, features and 25 advantages of my invention are set forth in the following description of a specific embodiment thereof as illustrated in the accompanying drawings wherein:

Fig. 1 is a cross section through my oil 30 burner as installed in the combustion chamber of a boiler;

Fig. 2 is a detail section enlarged from Fig. 1 and showing the structure for effecting the oil feed from the fuel supply conduit on to 35 the rotary atomizer;

Fig. 3 is a transverse plan section taken on line 3—3 of Fig. 2; and

Fig. 4 is a greatly enlarged detail section taken from Fig. 2.

40 A hollow spindle 10 is journaled by ball bearings 11 in a gear casing or body 12, and is driven through the bevel gears 13 by a horizontal drive shaft 14 extending from an electric motor or other source of power not shown. The gear case 12 is placed in the ash pit of a boiler beneath the floor of the combustion chamber, and carries at its upper end an atomizer 15 which protrudes through the bottom of a dish-shaped fire pot 16, thus forming 45 the floor of the combustion chamber. At

its upper end the atomizer 15 is outwardly flared to form a discharge lip beneath which are radially arranged sirocco fan vanes 17 generating a horizontal outward primary air supply beneath the discharge lip of the atomizer. The path of the air emanating from these sirocco fan vanes is controlled by an air ring 18 the inner margin of which acts as a block-off ring to regulate the air. The air ring 18 is vertically adjustable by a supporting cam ring 19, the lower periphery of which rests on a set of rollers 20 fixed on a stationary hearth ring 21. Suitable means may be supplied for rotating the cam ring 19 from without the furnace walls for effecting the vertical adjustment of the air ring 18. Such vertical adjustment also varies the opening in the annularly arranged ports 22 beneath the outer edge of the air ring 18. This provides a variable auxiliary air supply preferably 55 under natural draft.

The hearth ring 21 and the fire pot 16 may be supported by suitable posts 23 and preferably independently of the gear case 12 so that vibration of the latter is not imparted 60 to the combustion chambers.

Fuel oil for the burner is fed from a source of supply through a pipe 25 and into a base member 26 from which it passes through an upwardly extending standpipe 27. The pipe 25, base member 26 and standpipe 27 are 65 preferably mounted more or less independently from the gear case 12 to lessen danger of vibration and also to permit the case 12 and its associated parts to be lifted upwardly 70 from the standpipe when dis-assembling the burner.

The upper end of the feed standpipe 27 extends into the throat of the atomizer 15 and is there provided with a distributing 75 cap 28 generally cylindrical in exterior conformation. The central bore of the distributing cap 28 which forms a continuation of the bore of the standpipe 27 does not extend through the top of the cap but communicates 80 with three obliquely and radially drilled ducts 29, which lead to the periphery of the cap above a slightly shouldered cylindrical portion 95 85

The atomizer 15 preferably carries a cor- 100

responding shoulder 31 on the inner surface of its throat and laterally opposite the shoulder of the stationary cap. A very slight annular cylindrical space is thus left between 5 the shoulder of the portion 30 of the stationary cap and the corresponding portion of the throat of the atomizer. The atomizer rotates at so high a rate of speed that the oil as it flows on to the upper face of the shouldered portion 30 is immediately drawn across the intervening gap on to the interior surface of the atomizer. The shoulder 31 of the atomizer offers an immediate outward rotary travel for the oil under centrifugal 10 action to accelerate the flow of the oil across this intervening gap. From this point the oil flows upwardly along the slightly tapered interior wall of the atomizer under centrifugal action.

20 As a result of this method of feed the oil is transferred from the stationary feed member on to the rotary atomizer member in substantially a continuous film and over an annular region, as distinguished from being 25 transferred in drops. The advantage of this continuous action is that it will sustain a continuity of the oil flow at very low feeds in gallons per hour, and enable a low fire to burn evenly and without interruption.

30 To prevent the leakage of lubricant from the gear case 12 on to the lower part of the pipe 27 and its associated parts, and thence on to the floor of the ash pit, I provide an up-standing tube 32 extending from a fluid tight 35 fit in the bottom wall of the gear case 12 to a point not far below the upper end of the standpipe. A thimble member 32' is secured to the inner surface of the upper end of the spindle 10 and has upper and lower 40 tubular portions extending at a space inwardly from the bore of the spindle. The lower of these—32A—extends into the upper end of the stationary tube 32. The upper of these—32B—extends substantially to the bottom edge of the distributing cap 28 and forms, together with the lower inner wall of the throat of the atomizer, an annular 45 pocket 33 in which will be trapped any un-atomized oil which drains back from the walls of the atomizer after the atomizer stops rotating. When the atomizer again starts rotating, fuel oil collected in this annular pocket 33 will be carried upwardly 50 along the slightly tapered wall 34 of the atomizer past the transfer gap opposite the cylindrical portion 30 of the cap, and on upwardly along the wall of the atomizer.

55 Should any fuel oil get into the space between the thimble 32' and the standpipe 27, it will fall down into the space between the stationary tube 32 and the standpipe 27, whence it will flow out through the annular bottom opening 35 in the gear case 12 and on to the floor of the ash pit. Such oil will 60 not dilute the lubricating oil in the case 12.

The bottom opening 35 of the casing, the space between the standpipe 27 and the stationary tube 32 and the thimble 32' forms a central air passage for the upward flow of air along the exterior of the standpipe 27. 70 It will be noted that the air passage is radially without the oil passage below the point of oil transfer. Above the point of oil transfer the oil will have to be radially without the air. The air and oil must therefore radially cross each other's path at the point of the oil transfer from the stationary feed cap to the rotary atomizer. This crossing over of the air and oil should preferably be done without bringing the two into contact, lest 75 the air prematurely vaporize the fuel or at least interrupt the continuity of its flow.

I have solved this problem by providing a set of vertical air passage holes 36 through the standpipe distributor cap radially without the central bore thereof and arcuately 80 between the ducts 29 thereof.

This central air supply serves to cool the spindle and the interior of the atomizer and counteract any ill effects from the heat of 90 the combustion chamber to which it is more or less subjected. Passing the air through holes in the distributor cap affords an effective means for keeping the cap cool. This is especially important because were the cap 95 to become excessively hot it would carbonize the fuel oil in its small passage ways and build up deposits which would soon close them, seriously impairing the fuel supply.

100 My burner as thus far described is substantially identical with that disclosed in my above mentioned co-pending prior application.

I have found, in the structure of my prior application, some tendency of the air passing upwardly through the thimble 32' and the air passages 36 in the head to draw in air from the annular pocket 33. This would cause a partial vacuum in the pocket 33 and tend to pull down the oil passing over the 110 annular gap between the stationary and rotary transfer members. As a result I find that fuel oil would be carried down to the under side of the head 28 and into the air 115 passages 36, whence it would be deposited on the head and trickle down into the space between the thimble 32' and the standpipe 27 and from there through the bottom opening 35 and on to the floor of the ash pit. To remedy 120 this I have restricted the effective opening from the annular pocket 33 into the passage for upwardly flowing air. I have done this by providing an auxiliary sleeve 37 which 125 securely fits over the bottom edge of the cap 28 and extends downwardly parallel to the upper end of the portion 32B of the thimble 32' but at a very slight distance therefrom. This permits a sufficient practical clearance in view of the fact that the member 37 is stationary and the member 32B is rotating at a 130

high rate of speed, but the relative vertical distance in which the two are brought into parallelism materially aids in lessening the probable air flow through the space. I prefer that the bottom edge of the auxiliary sleeve 37 be turned inwardly somewhat further to restrict the opening.

As a result I find so far as any tendency to cause leakage is concerned the pocket 33 is sufficiently air tight. However, a sufficient working clearance is allowed for the relative rotation of the two parts and there is sufficient air passage to permit of the exhausting under centrifugal force of any fuel oil which collects in the pocket 33.

As a further improvement in my burner I provide a cover member. This cover member is not only for an insulating effect but a protection for the fuel transfer mechanism against dirt or other foreign matter falling down into the throat of the atomizer. For this purpose I provide a socket member 41 on the upper end of the distributor cap 28. The lower end of the stem 42 is taper fitted into this socket and at a point about opposite that at which the atomizer starts to taper upwardly and outwardly, the stem carries a cup 43. The stem extends upwardly beyond the cup 43 and supports a larger cup 44. While both cups 43 and 44 may be employed, as I have shown in Fig. 1, it is not necessary that both be employed, and either one or the other may be used alone.

The upper cup 44 is spaced sufficiently away from the lip of the atomizer to permit a certain cleaning of the atomizer without removing the cup. For cleaning, the cups alone or the cups and the stem may be removed. If the cup 44 is not used, but only the cup 43 is used, the cup 43 will form a convenient stop for the cleaning rod which will prevent the cleaning rod being inserted farther down in the throat of the atomizer than carbon deposits customarily occur under adverse conditions.

While I have thus described my invention in the particular embodiment shown, I contemplate that many changes may be made therefrom without departing from the scope or spirit of my invention.

I claim:

1. An oil burner comprising a vertically positioned rotary nozzle having an upwardly and outwardly tapering discharge opening, a stationary oil supply conduit extending into the interior of the nozzle, a stationary tip for said conduit having an annular distributing surface extending outwardly from the tip closely to the inner wall of the nozzle, means for conducting oil from the conduit to said annular distributing surface, said surface distributing oil directly onto the inner wall of the nozzle, a thimble rotating with the nozzle and having an upwardly extending portion spaced from said conduit, and a depending

sleeve on said tip extending closely to said upwardly extending portion of the thimble for substantially preventing the passage of air therebetween.

2. An oil burner comprising a vertically positioned rotary nozzle having an inverted bell-shaped discharge opening, a spindle for rotating said nozzle, an oil supply standpipe extending to the interior of said nozzle, a cap for said standpipe having an annular distributing surface extending outwardly closely to the inner wall of the nozzle, means for conducting oil from said standpipe to said annular distributing surface, air passageways extending vertically through said cap, and means for substantially preventing the creation of a vacuum in the space immediately below said distributing surface.

3. An oil burner comprising a vertically positioned rotary nozzle having an inverted bell-shaped discharge opening, a spindle for rotating said nozzle, an oil supply standpipe extending to the interior of said nozzle, a cap for said standpipe having an annular distributing surface extending outwardly closely to the inner wall of the nozzle, means for conducting oil from said standpipe to said annular distributing surface, vertical air passages through said cap, a thimble in said spindle, having extensions thereon forming an air passageway along said standpipe, leading to said vertical air passages, and a depending sleeve on said cap extending along and adjacent the upper extension of said thimble for substantially preventing the flow of air therebetween.

4. An oil burner comprising a vertically positioned rotary atomizer having an inverted bell-shaped discharge opening, a spindle for supporting and rotating said atomizer, an oil supply standpipe extending to the interior of said atomizer, a cap for said standpipe having an annular distributing surface extending outwardly into close proximity with the inner wall of the atomizer, means for conducting oil from said standpipe to said annular distributing surface, a thimble in said spindle spaced from said standpipe and forming an air passageway therealong, vertical air passages through said cap above said passageway, an extension on the upper end of said thimble spaced from said spindle and forming an annular oil receiving pocket, and a sleeve fitted to the lower end of said cap and extending closely to said extension for substantially preventing the circulation of air through said pocket.

5. An oil burner comprising a vertically positioned rotary nozzle having an inverted bell-shaped discharge opening, a spindle for rotating said nozzle, an oil supply standpipe extending to the interior of said nozzle, a cap for said standpipe having an annular distributing surface extending outwardly closely to the inner wall of the nozzle, means for

conducting oil from said standpipe to said annular distributing surface, vertical air passages through said cap, a thimble in said spindle having extensions thereon forming an air passageway along said standpipe leading to said vertical air passages, a sleeve snugly fitted to the lower periphery of said cap below said distributing shoulder and on a vertical line with the outer edge thereof, said sleeve having a horizontal portion seated on the lower edge of said cap, and a depending portion extending along said thimble extension in close proximity therewith, the extreme lower end of said sleeve being turned toward said extension for further restricting the passage therebetween.

6. An oil burner comprising a vertically positioned rotary atomizer having an inverted bell-shaped discharge opening, a spindle for supporting and rotating said atomizer, an oil supply standpipe extending to the interior of said atomizer, a cap for said standpipe having an annular distributing surface extending outwardly into close proximity with the inner wall of the atomizer, means for conducting oil from said standpipe to said annular distributing surface, a thimble in said spindle spaced from said standpipe and forming an air passageway therealong, vertical air passages through said cap above said passageway, an extension on the upper end of said thimble spaced from said spindle and forming an annular oil receiving pocket, and means on said cap surrounding the upper end of said extension for substantially preventing the movement of air upwardly through said vertical passages, from evacuating said pocket.

7. In an oil burner the combination of a vertically mounted, rotary nozzle having an upwardly and outwardly tapering discharge opening for atomizing liquid fuel, a fuel supply standpipe extending into the interior of the nozzle, fuel transfer means on said standpipe, cooling means for said nozzle, comprising, air passageways admitting an upward draft of air through said nozzle, an oil receiving pocket below said transfer means and a depending sleeve extending into said pocket at the inner side thereof for preventing the upward draft of air from causing a circulation of air through said pocket.

8. In an oil burner the combination of a vertically mounted, rotary atomizing nozzle having an upwardly and outwardly tapering discharge opening for atomizing liquid fuel, a spindle for supporting and rotating said nozzle, a stationary fuel supply standpipe extending into the interior of the nozzle, an annular fuel distributing surface for said standpipe, the periphery of said surface extending sufficiently near the inner surface of the rotary atomizer that the fuel is caused to flow horizontally across the open space therebetween, means for directing an up-

ward flow of air through said spindle and said atomizer, a pocket beneath the open space across which the fuel flows, and a stationary sleeve depending along the upper end of said air directing means for preventing the evacuation of said cup and the drawing of fuel downwardly through said open space.

9. In an oil burner the combination of a vertically positioned rotary atomizer, having an upwardly and outwardly tapering discharge opening, for atomizing fuel oil, a spindle for said atomizer, an oil supply standpipe extending to the interior of said atomizer, a stationary distributing cap for said standpipe, having an annular distributing surface extending outwardly toward the inner wall of the atomizer and forming an annular air gap therebetween, said air gap being of such size that oil flows directly and horizontally across the gap from the distributing cap to the atomizer, a thimble in said spindle spaced from said standpipe and forming an air passageway therealong, vertical air passages through said cap above said passageway, an extension on the upper end of said thimble spaced from said spindle and forming an oil receiving pocket, means on said cap depending along said extension for preventing the upward movement of air through said passages, from evacuating said pocket and drawing oil down through said air gap.

In witness whereof, I hereunto subscribe my name this 26th day of October, 1928.

FRANKLIN HARDINGE.
